SPINNING OR TWISTING DEVICE

George H. Gilligan, Providence, R. I., assignor to
 U. S. Ring Traveler Company, Providence, R. I.,
 a corporation of Rhode Island

Application May 15, 1933, Serial No. 671,117

1 Claim. (Cl. 118—59)

My invention relates to rings and ring travelers of the vertical type for spinning and twisting machines.

More particularly the present invention applies to rings and travelers wherein a constituent part of the traveler head includes a downwardly and rearwardly directed nose disposed to prevent accidental disengagement of the thread from the head, and to maintain the traveler shank in contact with the inner face of the ring. Such a construction is disclosed in Letters Patent of the United States No. 1,860,084 issued to me Sept. 27, 1932, and on which the present invention is an improvement.

In this type of traveler the free end of the nose is, in running position, in contact with or closely adjacent to the outer face of the ring, and, in threading position, the nose is so slightly interspaced from the latter that the insertion of the delicate thread or filament into the traveler head through the restricted space between the nose end and ring prior to starting the spindle, or in other words "piecing up the end," has a tendency to split, separate, or abrade the filament.

Essential objects of my invention are, while retaining the advantages inherent in a traveler nose disposed downwardly and inwardly towards the outer face of the ring, to avoid injury to the filament during the threading operation; to facilitate the introduction of the filament into a ring traveler head; to prevent accidental escape of the same therefrom; and to attain these results in a simple, strong, and inexpensive structure adapted for operation upon internally recessed or non recessed rings.

To the above ends primarily my invention consists in such parts and in such combinations of parts as fall within the scope of the appended claim.

In the accompanying drawing,

Figure 1 is a perspective diametrical section of a spinning or twisting ring carrying my novel traveler in running position thereon.

Figure 2, a fragmentary plane section of the ring showing the traveler in threading position,

Figure 3, a perspective view of the traveler,

Figure 4, a fragmentary plane section of a non-recessed ring showing a modified form of traveler mounted thereon in threading position, and

Figure 5, a side elevation of a second modified form of my novel traveler.

Like reference characters indicate like parts throughout the views.

As herein illustrated 12 represents a spinning

or twisting ring of the vertical type, seated in the usual ring rail 13 of a spinning or twister frame.

My novel traveler of the vertical type 15 is formed from a wire or rod of any desired or preferred cross sectional contour. It comprises an elongated shank 16, a foot 17 upon its lower end, and a head 18 connected to the upper end of the shank by a bend 19. The head includes a base portion 20 extending rearwardly and upwardly from the bend, thence a forwardly extending top portion 21, and then a nose portion 22 extending downwardly and rearwardly towards the traveler shank and toward the outer face of the ring as well as in substantial alignment with the bend 15, and in the vertical plane of the remainder of the traveler. Integral with the free end of the nose portion is an open loop 24 whose convex intermediate or bearing portion 25 is directed towards the ring, and its free end portion 26 is directed upwardly and forwardly.

The bearing portion 25 is spaced from the upper portion of the shank 16 preferably approximately the width of the thickness of the ring when intended primarily for lubricant spreading purposes, but when the desired function of the traveler is solely the retention of the filament from accidental escape from the traveler head the space between the shank and bearing portion may if desired be greater than that indicated.

The ring 12 is provided with one or more, in this instance two, lubricating recesses or grooves 28. Such grooves are shown in Figures 1 and 2. These grooves may, if desired, be omitted, as shown in Figure 4, if the lubricant has been initially manually applied to the inner surface of the ring, or if the sole desired purpose is the prevention of accidental escape of the thread or filament from the traveler head.

The form of traveler head may be changed to accommodate different diameters of the fibers to be twisted provided that the nose portion be inwardly and downwardly directed and its described terminal loop or its equivalent be present.

A modified form of my novel traveler is shown in Figure 4 and includes an open loop 30 from whose bearing portion 31 its free end 32 is directed forwardly and upwardly upon the side of the nose opposite to that of the end portion 26 of the loop 24. In the modification shown in Figure 5 the bearing member consists of a closed loop 33 wherein the loop end 35 overlaps the nose.

To perform the threading operation the spindle is stopped, which releases the tension on the filament 36 and the traveler is relaxed from its running position shown in Figure 1 and assumes

a slack vertical position hanging loosely by its head from the upper edge of the ring, with its foot 17 depending slightly below the lower edge thereof. The traveler is next manually elevated 5 lifting the loop 24 out of contact with the ring affording, as shown in Figure 2, a space or channel 37 for the insertion of the filament 36, held horizontally, therethrough into the interior of the head as at 38, and the traveler allowed to 10 drop into depending position. When the spindle is restarted the traveler and filament resume their original running positions. In Figure 2 the filament is shown about to be inserted.

In running position the contact of the loop 15 with the ring prevents accidental escape of the filament from the ring, but escape occasionally occurs while the spindle is inactive and the ring rail is continuing its traverse action with the traveler in slack position. Under these conditions, the torsional energy stored in the filament creates one or more tightly twisted stiff loops which sometimes elevate the traveler, and the unlooped portion of the filament crawls from 20 its position shown in Figure 1 along the top of

the ring and downwardly along the nose, and would escape between the traveler and ring were it not that the loop or loop ends 26 and 35, in the path of the moving filament, prevents further downward travel of the filament.

I claim:—

In combination, a ring having an inner face and an outer face, a traveler having a shank engageable with said inner face, a foot extending across the bottom edge of the ring, and a head 10 including an inwardly and upwardly and then outwardly directed top portion adapted to engage with the top edge of the ring, an inwardly and downwardly directed nose portion upon the outward end of the top portion, and a loop comprising a convex bearing portion formed by bending inwardly and upwardly said nose portion, said loop engageable with the outer ring face when the traveler is in running position and terminating in a free end portion extending 15 upwardly and outwardly and lying between said nose portion and the outer face of the ring.

GEORGE H. GILLIGAN.
